United States Patent Office

Des. 224,275
Patented July 11, 1972

224,275

POWER BOAT

Richard C. Cole, 19701 Whispering Pines Road,
Miami, Fla. 33157

Filed Dec. 21, 1970, Ser. No. 26,606

Term of patent 14 years

Int. Cl. D12—06

U.S. Cl. D71—1

FIG. 1 is a side elevational view of a power boat showing my new design.

FIG. 2 is a top plan view thereof.

FIGS. 3 and 4 are front and rear elevational views, respectively.

FIG. 5 is a bottom plan view.

I claim:

The ornamental design for a power boat, substantially as shown.
